BATTERY POWERED MOTOR DRIVEN SHOE BRUSH

Alvin Polatchek, New York, N.Y., assignor to Shields,
Inc., Attleboro, Mass., a corporation of Massachusetts

Filed Mar. 2, 1964, Ser. No. 78,836

Term of patent 14 years

(Cl. D9—2)

FIG. 1 is a side elevational view of a battery powered motor driven shoe brush showing my new design;

FIG. 2 is a rear elevational view thereof;

FIG. 3 is a bottom plan view thereof;

FIG. 4 is a front elevational view thereof;

FIG. 5 is a top plan view thereof; and

FIG. 6 is a side elevational view looking at the opposite side from that shown in FIG. 1, a portion of the rotary brush being deleted for convenience of illustration.

I claim:

The ornamental design for a battery powered motor driven shoe brush, as shown.
